UNITED STATES PATENT OFFICE.

ALLEN ROGERS, OF BROOKLYN, NEW YORK.

OIL-CRACKING PROCESS.

1,378,424.

Specification of Letters Patent. Patented May 17, 1921.

Application filed June 1, 1920. Serial No. 385,646.

To all whom it may concern:

Be it known that I, ALLEN ROGERS, a citizen of the United States, residing at Brooklyn, in the county of Kings and State of New York, have invented certain new and useful Improvements in Oil-Cracking Processes, of which the following is a specification.

This invention relates to oil cracking processes; and it comprises a method of producing large yields of motor fuel of the gasolene type from various higher boiling oils, wherein such higher boiling oil is vaporized, as in the presence of steam under conditions and at a temperature, say about 600° F., giving thorough vaporization and the mixed vapors are thereafter progressively heated to a comparatively low cracking temperature, say, around 800° F., the vapors after reaching this temperature being cooled and condensed and the motor fuel produced recovered; all as more fully hereinafter set forth and as claimed.

As is well known in the art, motor fuels of the gasolene type can be produced from most higher boiling oils, such as kerosene, gas oil, solar oil, fuel oil, still residues, etc., by heating to a temperature above, say, 600° F. The heavier oils under these conditions break down into lighter oils. It is not very material as regards the cracking whether the oil be in the liquid or the vapor form, except that in the case of liquid oil in order to attain temperatures above 600° F., it is in general necessary to operate under pressure. Cracking of vapors may also be done under pressure in order to secure somewhat greater capacity of apparatus; it being of course possible to get twice as much vapor in a given chamber under 15 pounds gage pressure as under atmospheric pressure. The difficulty arises however that all the oils which it is desirable to crack into gasolene boil at relatively high temperatures; many of them not beginning to boil below 600° F. and all of them containing portions which boil far above that temperature. Therefore in compressing the vapors of any high boiling oil it is difficult to prevent more or less of the vapor going over to liquid even at cracking temperatures, that is above 600° F. In cracking oil in the liquid form under pressure the action is tolerably uniform and the same is true where vapors free of liquid, that is, "dry vapors," are cracked. But if

the cracking heat be applied to a mixture of liquid and vapor, the operation becomes irregular and hard to control; this being for the simple reason that vaporizing liquid oil absorbs much heat. As it is difficult to produce a suspension of oil in oil vapors of any constant composition, it is obvious that such a mixture cannot readily be cracked under constant conditions.

It is the object of the present invention to provide a process wherein cracking shall be under readily controllable conditions and to this end I take advantage of the fact that all the petroleum oils, even the highest boiling, can be converted into vapors without substantial cracking if vaporization be done in the presence of a current of steam; a fact which is at the basis of the ordinary practice of using bottom steam in distilling lubricating oil, wax oil, wax, etc. In the present invention I spray or mist a high boiling oil into a current of steam in such proportion that the oil will be substantially completely volatilized; that is, everything except residual pitch-like or asphaltic constituents. The proportion of steam to oil is made as small as will just secure this result of uniform volatilization, and the operation is performed at about the temperature which experience has shown, in oil distillation, to be the maximum practicable for vaporization without much cracking, namely about 600° F. At 600° F., as stated, most or all oils can be converted into vapors in the presence of steam without much decomposition or cracking; and in this stage of the operation I desire to secure, as nearly as may be, unchanged oil vapors. The mixture of steam and oil vapors, having once been made, is next exposed to as low a cracking temperature as will suffice to give a good yield of motor fuel. It is best to heat progressively from the initial non-cracking temperature of 600° F. up to about 800 F. With a methodical and progressive heating, if the temperature does not finally much exceed 800 F., there is relatively little loss in the production of gas and in the concomitant production of coke and tar. The temperature referred to are those of the vapors themselves; not of the tubes or the like through which the vapors pass. The temperature of the tubes may be, and ordinarily is, much higher; but this is immaterial. The flow of mixed vapors is so controlled with

regard to the temperature of the tubes that the temperature of the vapors themselves shall be within the limits stated.

While many forms of apparatus may be used for the present purpose, I find it best to use a series of horizontal tubes so mounted in a furnace chamber as to be exposed to progressively higher temperatures. A convenient arrangement is to have a series of horizontal tubes in a vertical chamber fired at its base, each tube being connected with the one next above and next below by suitable connections. By using a T for this connection and giving an extension through the furnace walls at each end of the cracking tube proper, a straightway unobstructed passage is given by which the tube may be poked or barred out, thereby keeping the interior of the tubes clean and free of coke. The deposition of any substantial amount of carbon in the tubes is undesirable for several reasons; one being that it interferes with the regularity of heating here desired and another being that the presence of coke is apt to institute irregular catalytic reactions. It is therefore desirable to keep the amount of carbon in the tubes at a minimum. In order, further, to promote uniformity of heating, it is desirable to block out the center of each of the tubes by a central rod, thereby causing the mixture of vapors to travel next the inner periphery of the heating tubes as a thin annular layer. Cracking is a heat absorbing reaction and upon the regularity of the delivery of heat to the vapors depends much of the success of the operation; this being one of the reasons why the presence of unvaporized oil is undesirable. By blocking out the center of the tubes in this manner it is possible to obtain relatively thin annular layers of vapor through which it is not necessary for heat to pass any great distance, while at the same time securing the advantages of large sized apparatus. The interior elements used for blocking out the center of the tubes should of course be readily removable.

In the accompanying illustration, I have shown, more or less diagrammatically, certain apparatus within the present invention and useful in performing the described process. In this showing—

Figure 1 is a view in central vertical section, certain parts being shown in elevation, and

Fig. 2 is a fragmentary view in longitudinal section showing a method of connecting a blocking out pipe located in the cracking tube proper.

In the drawing, element 1 indicates as a whole a suitable furnace chamber fired at its base by burner 2. As shown, the burner gases strike a baffle wall 3 to give an even distribution of heat within the chamber, and

waste gases pass to outlet at 4. Within the furnace chamber are arranged several horizontal tubes in series; eight are shown. The uppermost tube 5, being most remote from the firing means, is at the lowest temperature. It is kept as nearly as possible at about 600° F. As shown, it is provided with inlet 6 leading through the walls of the furnace chamber to suitable connections (not shown) for supplying oil and steam. It is also provided with extensions 7 and 7' passing through the walls of the furnace. The two extensions serve to support the tube at the ends and to give a straightway channel for cleaning out purposes. Within the furnace chamber the tube is provided with a T connection leading to a similar tube 8 just below it. This latter tube is also provided with end extensions like the first described tube and for the same purpose. The tube 8 connects in turn by a T-connection 9 with another tube 10, and this in turn communicates with 11, 12, 13, 14 and 15 by T connections. The last mentioned tube carries outlet extension 16 taking vapors, gases and tarry products to suitable condensing and separating apparatus (not shown). The motor fuel is separated from the condensate by the ordinary distillation methods. As shown, the ends of the various tubes are located within wall recesses 17 and 18. In order to promote uniformity of heating of the mixture of steam and oil vapor going through the tubes, the tubes may be, as shown, provided with an interior blocking out rod 19 forming an annular passage around it. Because of the presence of this rod the vapors passing through the tubes are caused to travel in a relatively thin annular, easily heated layer. An even better effect may be secured by using a tube in lieu of a rod, for this blocking out member 19, and by causing hot products of combustion to travel through the tube. By so doing heat is applied both to the interior and to the exterior of the annular layer of oil vapor. Arrangements for this purpose are shown in the drawing. In the fire chamber is located suction tube 20 delivering hot products of combustion to riser 21 which communicates, as best shown in Fig. 2, with interior blockingout tube 19. As shown in Fig. 2, this tube 21 screws into a special nut 22 having a double threaded engagement with the cracking tube and with the interior blockingout tube. For cleaning purposes, the upright passage with which 21 communicates is extended through the nut and closed at the other end by plug 23. A similar connection is at each end of all the cracking tubes, thereby giving a continuous passage for the products of combustion going in at 20 throughout the system. From the top cracking tube 5 products of combustion

are removed through one of the extensions (7') which is connected to suitable exhausting or sucking means (not shown.)

The recesses in the walls for the accommodation of the ends of the tubular members may be, and advantageously are, closed by doors 24.

What I claim is:—

- 10 1. The process of cracking oil to form motor fuel and the like which comprises mixing such oil with about the right amount of steam to vaporize it at a temperature of 600° F., and produce a vapor mixture substantially free of liquid and progressively heating the mixture of steam and oil vapor from a temperature of about 600° F. to about 800° F., (as a thin traveling annular layer,) thereafter removing the vapors and condensing the cracked products formed.
- 15 2. A process of cracking oils to form motor fuel, which comprises mixing such oil with about the right amount of steam to vaporize it at a temperature of 600° F. and produce a vapor mixture substantially free

of liquid and progressively heating the mixture of steam and oil vapors from a temperature of about 600° F. to about 800° F. in tubes in a thin annular traveling layer, (heat being applied to said layer both internally and externally) and condensing the cracked products formed.

3. In the manufacture of motor fuel from heavier petroleum oils, the process which comprises converting such heavier oil into a vapor substantially free of liquid, passing such vapor in a thin current through an unobstructed annular channel under heating conditions adapted to raise its temperature to a point not substantially above 800° F. and diverting and cooling the vapors after attaining a temperature of about 800° F.

In testimony whereof, I affix my signature in the presence of two subscribing witnesses.

ALLEN ROGERS.
